United States Patent Office.

ELISHA KELLEY, OF LOCUST GROVE, OHIO.

Letters Patent No. 66,715, dated July 16, 1867.

IMPROVED BROOM-HEAD.

The Schedule referred to in these Letters Patent and making part of the same.

TO ALL WHOM IT MAY CONCERN:

Be it known that I, ELISHA KELLEY, of Locust Grove, in the county of Adams, and State of Ohio, have invented a new and improved Broom-Head; and I do hereby declare that the following is a full, clear, and exact description of the construction and operation of the same, reference being had to the accompanying drawings, making a part of this specification, in which—

Figure 1 of Sheet 1 is an end view of my improved broom-head.

Figure 2, a vertical longitudinal section, as indicated by the line *x y* of fig. 1.

Figure 3, an end view of the same, again showing a modification of the arrangement on which the broom is made.

Figure 4, a vertical longitudinal section, as indicated by the line *v p* of fig. 3.

Figure 5, of Sheet 2, a view showing position of broom-head when ready for filling.

Like letters, in the different figures of the drawings, indicate like parts.

The nature of my invention consists in the construction of two wire racks on which the broom is made, and two sides or casings, all suitably hinged to the head; one of the sides being so constructed as to form the ends and the edges thereof, and those of the other side so made as to form a clasp-joint for securing the sides or casings for fastening the broom to the head. The object of hinging the sides and the racks is that they may be entirely spread open, and thereby afford facility and convenience in the operation of making the broom.

It will be perceived, as will hereinafter be particularly described, that the simplicity of my improvement is such that its construction is attended with comparatively but little expense, and that almost any one can make a broom with it, and, besides, possessing an advantage in the readiness with which the sides or casings can be unclasped, and a new broom made when the old has worn out.

To enable any one skilled in the art to make and use my invention, I will proceed to describe its construction and operation.

A A represent the sides of heavy tin sheeting or brass suitably hinged to the head B of like material. One of the sides, in laying them off, is cut wider than the other, sufficiently to form the ends *a* of the broom-head. The edge of the ends and those of the other side are properly bent over, in reverse directions, to form clasps *b b b*. C C are the wire racks, constructed in the manner seen in figs. 2 and 5, and hinged to hooks, or in any suitable manner. D is a stay attached to screw-bolt connecting with broom-handle.

The sides and racks of the broom-head are spread open flatly, (see fig. 5 of sheet 2,) and the broom-stalks inserted in the holes of the racks until sufficiently full, when they are brought up and the sides closed and securely fastened by the edge of the end of one side clasping the edge of the other, and the joints thus made tightened with a hammer. In closing the sides the broom will become necessarily fastened to the racks by the sides bearing against the bent-over stalks of the broom. The stay, being in the centre of the two racks, will give a firmness to the head of the broom. The racks may be dispensed with, if desired, and a plate, E, (see figs. 3 and 4,) with semicircular perforations, attached the same as the stay, and the stalks filled in the perforations from both sides, and the casing or sides closed as above. This plate at the same time will answer the purpose of the stay. To divest the broom-head of as much weight as possible, and thus make it easier for the handling of the broom, I cut out pieces *c c* from the sides, and make the side with the ends about one-half, (see figs. 1 and 3.)

Having thus fully described my invention, what I claim therein as new, and desire to secure by Letters Patent, is—

1. The construction of wire racks, in combination with hinged or permanently fixed casings or sides, substantially in the manner and for the purpose as herein set forth.

2. The combination of the stay with the wire racks, substantially in the manner and for the purpose as herein set forth.

ELISHA KELLEY.
